TOBACCO FEEDING MECHANISM

James P. Durning, St. Albans, N. Y., assignor to
International Cigar Machinery Company, a
corporation of New Jersey

Application February 7, 1940, Serial No. 317,676

10 Claims. (Cl. 131—108)

This invention relates to tobacco feeding mechanism, and more particularly to improvements in devices for feeding short filler tobacco of a relatively small size.

According to my invention short filler tobacco is confined in a hopper provided with side and rear walls and a substantially horizontal bottom, and means are furnished to cooperate with the hopper in confining a supply of short filler tobacco. In feeding some types of short filler tobacco there have been used with this type of hopper movable rakes which are placed at the hopper outlet and serve both to confine and control the movement of the tobacco from the supply contained in the hopper by virtue of the movement of the rakes relative to themselves and the mass of tobacco confined in the hopper.

However when small scrap is used the rakes in themselves generally are not sufficient to hold the tobacco in the hopper because the tobacco will flow through them and flow uncontrolled from the hopper along the delivery portion which forms a part thereof, thereby upsetting the proper operation of the cigar machine with which the hopper is used.

It is, therefore, an object of my invention to provide mechanism for feeding small short filler tobacco wherein means are furnished to prevent an uncontrolled flow of the tobacco from the container in which the supply is stored.

It is a further object of my invention to provide a hopper having side and rear walls extending upward from a tobacco supporting bottom in which confining means assist in holding the tobacco in the hopper and controlling its flow therefrom during feeding operations.

It is an additional object of my invention to provide an adjustably mounted control member for storing a quantity of small scrap tobacco in a hopper so that controlled quantities of tobacco can be fed from the hopper.

My invention also consists in the provision of a hopper provided with a substantially horizontal tobacco supporting and feeding surface and a member which cooperates with this surface for confining tobacco therein, and movable devices which coact with said member in controlling the feed of tobacco from the hopper and along the feeding surface.

With these and other objects not specifically mentioned in view, the invention consists in certain combinations and constructions which will be hereinafter fully described, and then set forth in the claims hereunto appended.

In the accompanying drawings which form a

part of this specification and wherein the several reference characters designate the same or like elements:

Figure 1 is a sectional side elevation showing the preferred form of my invention for feeding small short filler tobacco;

Figure 2 is a partial sectional end elevation taken on line 2—2 of Figure 1;

Figure 3 is a sectional side elevation showing a modified form of a tobacco confining member;

Figure 4 is a partial view of a modified form of confining plate;

Figure 5 is a side view showing mechanism for intermittently vibrating the hopper and oscillating the rakes;

Figure 6 is a section taken on line 6—6 of Figure 5; and

Figure 7 is a suitable wiring diagram for use in intermittently vibrating the hopper and oscillating the rakes.

Referring to Figures 1 and 2 which show the preferred form of my invention, 10 designates a hopper employed for feeding short filler tobacco which may take substantially the form as that disclosed in my co-pending application, Serial No. 193,244, filed March 1, 1938, and wherein the hopper is provided with side walls 10a, a rear wall 10b and a bottom tobacco supporting surface 10c having an outlet chute 11 onto which the tobacco is fed from the supply during the feeding operation of the hopper. As shown in Figures 1, 2 and 5, surfaces 10c and 11 are joined by a step or shoulder formed integrally therewith.

Hopper 10, in the form shown, is resiliently supported by means of leaf springs 14 bolted to lugs 14a projecting from the bottom of the hopper (as shown in Figure 1) and is intermittently vibrated by means of a suitable device, described hereinafter, such for instance as that described in my above referred to application in which an electric vibrator 15 is adjustably mounted on a base block 16 suitably attached to the frame F of the machine. Extending upwardly from the frame of the machine are pedestals 21, 22 supporting at their upper ends, a housing 20. Housing 20 provides a mount for rakes 12 which are suspended from a bar 17 and rakes 13 which project from a bar 18, which bars are pivoted at their centers on a stud 19 mounted in the housing 20. One end of bar 17 is pivotally connected to an operating lever 24, and an end of bar 18 is connected in a similar manner to lever 23, both operating levers being pivoted on a stud

25 and provided at their free ends with cam followers 26 and 27, respectively, which engage the track of a drum cam 28 mounted on a rotating vertical shaft 29 supported in pedestal 22.

As shown in Figure 1, the tobacco confining member 30 is adjustably mounted on the rear face of housing 20. The plate is mounted rearwardly of the step or shoulder joining surfaces 10c and 11, and is arranged between the side walls 10a and substantially at right angles thereto, and is also located at substantial right angles with the tobacco supporting surface 10c and is spaced therefrom a predetermined distance in order to allow a portion of the tobacco, which it confines in the hopper, between the side and rear walls, to flow therebeneath onto the discharge or outlet chute 11 for delivery to a cigar machine. In the illustrated embodiment, member 30 is shown as comprised of a solid plate but if desired, this member could be composed of several closely positioned plates which would effect the same desired result. Plate 30, in this case (as shown in Figure 1) is made of a single piece of metal and is provided with slots 31 through which pass screws 32 by means of which it is adjustably and detachably secured to housing 20 in order that the space between the bottom of plate 30 and tobacco supporting surface 10c can be adjusted readily to control the tobacco passing through the aperture formed by the plate and surface 10c.

In Figure 4, the modified form mentioned hereinabove is shown, the tobacco confining member is made up of a plurality of closely spaced plates 30a each provided with an elongated slot 31a through which project screws 32 by means of which the plates 30a are positioned at a proper height above the deck of the hopper 10c.

According to Figure 3, which shows a modified form of my invention, a two-piece confining member is shown. This member consists of an upper part 33, which is detachably fixed to housing 20 by means of screws 32, while the lower portion 34 is provided with slots 36 through which project bolts 35 constructed and arranged to allow plate 34 to be moved relatively to and vertically with respect to plate 33 to control the height of plate 34 above surface 10c.

It will be seen, therefore, that my tobacco confining and flow control plate is adapted for selective operation either with or without rakes 12, 13. That is, whenever the tobacco is very small, the plate can be used without the rakes and substantially the same effect would be obtained in the uniform feed of tobacco from the confining portion of the hopper between the bottom edge of the plate 30 and the discharge surface 11 of the hopper. So also, if larger tobacco is to be fed, the plate 30 may be removed entirely in order that the rakes will act both to confine the tobacco in the hopper and control the feed therefrom along the discharge portion 11 thereof.

Figures 5, 6 and 7 show suitable mechanism for intermittently vibrating the hopper and oscillating rakes 12, 13 for feeding tobacco from the hopper. Hopper 10 is vibrated and rakes 12, 13 oscillated intermittently by mechanism similar to that disclosed in my co-pending application hereinabove referred to. Referring to Figures 5, 6 and 7, vertical rake operating shaft 29 is driven intermittently by means of a conventional type ball clutch 67 (Figure 6) from a conventional variable speed drive designated generally D secured in housing 56 (Figure 5). This

variable speed drive is connected by conventional driving means (not shown) with the main gear drive (not shown). Ball clutch 67 is carried by a ratchet 68 which, when engaging with a stationary pawl 69, causes the disengagement of shaft 29 from the continuously driven variable speed drive in housing 56 and thereby stops the motion of the rakes 12, 13.

10 Tobacco passing through the aperture formed by vertical plate 30 and surface 10c and between rakes 12, 13 is fed over surface 11 to a scale pan P located beneath the discharge lip of the hopper (as shown in Figure 5). Pan P, as in my co-pending application referred to hereinabove, consists of a substantially vertical plate 70 mounted on arm 73 fixed on shaft 74 carried by bracket 78 secured to bracket 79. Pivoted mounted on studs 80 carried by the upper portion of plate 70 is a scale receptacle 81 which with plate 70 forms the pan P.

15 Whenever a predetermined quantity of tobacco has been fed into scale pan P, it swings downwardly on shaft 74 thereby causing a mercury switch 81, connected in an electric circuit (see Figure 7) to break the circuit and de-energize vibrator 15. This operation stops the vibrating motion of hopper 10, and the oscillation of rakes 12, 13, thereby discontinuing the feed of tobacco to pan P. The rake oscillation is interrupted 20 upon the de-energization of relay R by means of solenoid 103 which is de-energized, thereby causing armature 102 connected by link 101 to lever 100 to withdraw lug 104 from engagement with finger 105 of pawl 69 against the tension of spring 106. Pawl 69 will move into engagement with ratchet 68 causing ball clutch 67 on shaft 29 to disengage the latter from the variable speed drive and thereby also stop the motion of rakes 12, 13. Lever 100 is pivotally mounted on a stud 25 shaft 98 connected by bearing lug 99 (Figures 5 and 6). When the machine is running, line switch 116 is closed.

20 The invention above described may be varied in construction within the scope of the claims, for the particular device, selected to illustrate the invention, is but one of many possible concrete embodiments of the same. It is not, therefore, to be restricted to the precise details of the structure shown and described.

25 What is claimed is:

1. In a tobacco feeding mechanism for cigar machines, the combination with a hopper provided with an upstanding back, connecting side walls and a substantially horizontal bottom provided with a discharge section, of a vertical support, relatively movable rakes comprising closely spaced downwardly extending prongs mounted in said support and positioned with their free ends proximate said bottom, and a plate mounted on said support and located between said side walls for confining tobacco in said hopper, said plate being so constructed and arranged that tobacco confined in said hopper may move beneath said plate and between said prongs of said rakes.

2. In a tobacco feeding device for cigar machines, the combination with a tobacco confining member provided with a substantially horizontal bottom supporting surface, a discharge section positioned in a plane substantially parallel to but below said surface and integrally joined thereto, of a support, a stationary tobacco confining plate mounted on said support and located above and at an angle to said bottom supporting surface and spaced therefrom to form a feed aperture for tobacco, a plurality of rakes com-

prising closely spaced depending fingers located above said section with their ends adjacent said surface but below the level thereof, and means for moving said rakes to allow tobacco fed beneath said plate to pass between said fingers and be fed into a stream over said section.

3. In a tobacco feeding device for cigar machines, the combination with a tobacco holding member provided with a substantially horizontal bottom supporting surface constructed and arranged to hold a bulk supply of tobacco sufficient to form a large number of cigars, said surface having a discharge section, of a support, a stationary tobacco confining plate coacting with said surface to prevent uncontrolled feed of tobacco from said bulk supply mounted on said support and located above and at an angle to said bottom supporting surface and spaced therefrom to form a feed aperture for tobacco, and a plurality of relatively movable rakes positioned closely adjacent said aperture coacting with said plate and surface to distribute tobacco fed through said aperture from said hopper between said rakes upon said section.

4. In a tobacco feeding device for cigar machines, the combination with a tobacco confining mechanism provided with a substantially horizontal bottom supporting surface constructed and arranged to support a bulk supply of tobacco which is unreplenished during a large number of cycles of operation of the machine, and a discharge section, of a support, a plate member mounted on said support and located above and at an angle to said bottom supporting surface and spaced therefrom to confine said bulk supply of tobacco in said hopper and form the sole feeding aperture for tobacco to be fed from said supply, a plurality of rakes coacting with said member and surface, and means for effecting relative motion between said surface, rakes and plate for feeding tobacco through said aperture and past said rakes over said section.

5. In a feeding device for short filler cigar machines, the combination with a hopper provided with a generally horizontal supporting and feeding surface, said hopper having spaced side walls and a connecting rear wall, of means for intermittently vibrating said hopper to feed tobacco to said surface, stationary means spaced from said surface a predetermined distance to control the quantity of tobacco fed during the vibration of said surface, and a plurality of movable rakes also located above said surface adjacent to and coacting with said means in feeding said tobacco therebetween from said hopper.

6. In a tobacco feeding device for short filler cigar machines having a hopper provided with end and side walls, and a bottom supporting surface containing a bulk supply of tobacco sufficient to form a large number of cigars and a feeding surface for tobacco fed from said bulk supply, and means for intermittently vibrating said hopper and the entire bulk supply of tobacco contained therein to feed controlled quantities therefrom, a plate located at substantially right angles and closely adjacent to said side walls and above said surface for confining tobacco in said hopper, means for mounting said plate a predetermined distance above said surface to control the quantity of tobacco issuing from said supply contained in said hopper in a stream during each vibration of said hopper, rakes coacting with said plate in feeding said tobacco therebetween as it moves beneath said plate for movement over said

surface, and means for intermittently oscillating said rakes.

7. In a tobacco feeding device for a cigar machine, the combination with a tobacco confining mechanism provided with a substantially horizontal bottom supporting surface and a discharge section, of a support, a plate member mounted above said surface and forming an aperture therewith coacting with said surface to confine tobacco and prevent unlimited feed thereof along said surface, a plurality of rakes coacting with said plate and surface, means for moving said rakes across said aperture, means for effecting relative motion between said surface and plate during the movement of said rakes for feeding tobacco through said aperture past said moving rakes in a stream onto said section, and means for detachably mounting said member for selective operation on said support.

8. In a material feeding device, an open receptacle provided with an elongated bottom and material enclosing upstanding back and side walls, means for mounting said receptacle to support it with the bottom thereof in a substantially horizontal plane, said bottom being provided with a single transverse connecting shoulder forming an integral part of said hopper, and dividing said hopper bottom into a tobacco holding portion wherein that portion of the bottom bounded by said side and back walls is inclined downwardly and rearwardly from the horizontal plane towards said back wall and downwardly and rearwardly from the horizontal plane towards said side walls, and a bottom tobacco feeding portion lying in a plane below the first-named bottom portion and over which a stream of tobacco may be fed, said feeding portion being inclined downwardly from a horizontal plane in a direction opposite to the inclination of said first-named portion, a stationary support above said hopper, a stationary plate mounted on said support and located above the surface of said tobacco holding portion and rearwardly of said shoulder, means detachably mounting said plate on said support, and means for vibrating said hopper to feed tobacco beneath said stationary plate and from said hopper.

9. A material feeding hopper of the vibratory type comprising a receptacle provided with back and side walls rising substantially vertically from an elongated bottom surface having a discharge section and an integrally connected tobacco holding section arranged at an angle inclining downwardly and rearwardly from a horizontal plane between said side walls towards said back walls to contain a mass of tobacco, a single transverse shoulder forming an integral part of said hopper bottom positioning said tobacco holding section vertically above said discharge section, said surface of said discharge section being inclined downwardly from a horizontal plane in a direction opposite to the inclination of said holding section, means for resiliently supporting said hopper, a support, a plate member detachably mounted on said support and located above said tobacco holding section and rearwardly of said shoulder, said plate being constructed and arranged to hold back said mass of tobacco in said hopper and form with the surface of said section a delivery aperture for tobacco, and means for intermittently vibrating said hopper and the mass of tobacco therein to feed a stream of tobacco beneath said plate from said holding sec-

tion and over said discharge section of said hopper.

10. A material feeding hopper of the vibratory type comprising a receptacle provided with back and side walls rising substantially vertically from an elongated bottom surface having a discharge section and an integrally connected tobacco holding section arranged at an angle inclining downwardly and rearwardly from a horizontal plane between said side walls towards said back walls 10 to contain a mass of tobacco, a single transverse shoulder forming an integral part of said hopper bottom positioning said tobacco holding section vertically above said discharge section, said surface of said discharge section being inclined downwardly from a horizontal plane in a direction opposite to the inclination of said holding section, a tobacco confining plate member located

15 a predetermined distance above said tobacco holding section and rearwardly of said shoulder to define a tobacco feeding aperture therewith, means for mounting said plate at an angle with the surface of said section transversely of said hopper and closely adjacent said side walls to hold back said mass of tobacco in said hopper and insure the passage of tobacco through said aperture only, said last-named means including devices for adjustably securing said plate in operative position relative to said holding section, and means for vibrating said hopper and the entire mass of tobacco therein to feed a stream of tobacco beneath said plate member from said holding section and over said discharge section from said hopper.

JAMES P. DURNING.
